UNITED STATES PATENT OFFICE

JERRY SILL, OF CHICAGO, ILLINOIS, ASSIGNOR TO AMERICAN ENVELOPE COMPANY,
OF CHICAGO, ILLINOIS, A CORPORATION OF ILLINOIS

DESIGN FOR A HAT

Application filed September 6, 1930. Serial No. 36,890. Term of patent 7 years.

To all whom it may concern:

Be it known that I, JERRY SILL, a citizen of the United States, residing at Chicago, in the county of Cook and State of Illinois, have invented a new, original, and ornamental Design for a Hat, of which the following is a specification, reference being had to the accompanying drawing, forming part

The figure is a perspective view of a hat showing my new design, the same being illustrated on the representation of the head of the wearer indicated in dotted lines. Both sides of the hat are alike.

I claim:

The ornamental design for a hat substantially as shown and described.

JERRY SILL.
